Application January 24, 1942, Serial No. 105,404

Term of patent 14 years

To all whom it may concern:

Be it known that I, Edwin R. Goldfield, a citizen of the United States, residing at University Heights, in the county of Cuyahoga and State of Ohio, have invented a new, original, and ornamental Design for an X-Ray Tube Head, of which the following is a specification, reference being had to the accompanying drawing, forming part thereof.

In the drawing, Fig. 1 is a perspective view;

and Fig. 2 is a top plan view of an X-ray tube head showing my new design.

The sides not shown in the drawing are substantially the same as the corresponding sides shown.

I claim:

The ornamental design for an X-ray tube head, as shown and described.

EDWIN R. GOLDFIELD.
